Primary Examiner — Elizabeth J Oswecki*(74) Attorney, Agent, or Firm* — Peter L. Olson**(57) CLAIM**

The ornamental design for an ear muff attachment arm, as shown and described.

DESCRIPTION

FIG. 1 is a perspective view of an ear muff attachment arm showing our new design;

FIG. 2 is a front view thereof;

FIG. 3 is a rear view thereof;

FIG. 4 is a left side view thereof, the right side being a mirror image thereof;

FIG. 5 is a top view thereof; and,

FIG. 6 is a bottom view thereof.

Broken lines form no part of the claimed design, and any shading is provided to illustrate contour only and is not an indication of texture, gloss, etc.

The shaded surface areas up to the broken lines define the boundary of the claim.
